DENTAL PLATE CLEANSER

Filed Dec. 23, 1938

INVENTOR:
SAMUEL JELLINEK,

By Harry A. Benner
ATTORNEY.

UNITED STATES PATENT OFFICE

2,160,149

DENTAL PLATE CLEANSER

Samuel Jellinek, St. Louis, Mo.

Application December 23, 1938, Serial No. 247,348

2 Claims. (Cl. 15—27)

My invention has relation to improvements in dental plate cleansers, and consists in the novel features of construction more fully set forth in the specification and pointed out in the claims.

5 This invention embodies all of the subject matter of that of my application Serial No. 213,737, and in addition thereto embodies features more fully hereinafter explained. The invention is more particularly directed to a rotary operating brush 10 for application to dental plates whereby the accumulations and deposits to which they are subject may be thoroughly and expeditiously removed.

The principal object of the invention is to 15 provide a circular brush rotatably mounted on a suitable handle so that it may be rolled over the dental plate to cleanse the same. The brush is of course circular and the bristles are rounded at the periphery so as to conform to the shape 20 of the fillet joining the gum portion of the plate to the main body thereof.

Other objects of the invention will be better 25 apparent from a detailed description of the same in connection with the accompanying drawing, in which:

Figure 1 is a perspective view showing my improved brush being applied to an upper dental plate; Fig. 2 is a side elevation of the brush; Fig. 3 is a side elevation of the upper part of the 30 brush looking at the opposite side from that shown in Fig. 2; Fig. 4 is a vertical longitudinal section taken on the line 4—4 of Fig. 2; and Fig. 5 is a detail view of the slot and removable pin construction.

35 Referring to the drawing, P represents an upper dental plate, having the usual body portion a joined to the gum portion b by a fillet c. The fillet c is the most difficult part of the plate to clean because brushes of the usual construction are not readily admitted into the space between the gum portion b and body portion a. Furthermore, the curvature of the fillet c makes it extremely difficult to pass a brush back and forth through this fillet.

40 I accordingly have devised a brush B, comprising a handle 1, in which is secured a shank 2 flattened at its upper extremity 3, in which there is an opening 4 to receive a stem 5, the head 6 of which is brazed or otherwise securely 45 fixed in the extremity 3 of said shank 2. A shoulder 7 is provided between the head 6 and stem 5, and a shoulder 8 is provided between said stem and a terminal screw portion 9.

The brush proper comprises a hub 10 in which 50 are mounted a mass of bristles 11 arranged

circularly around the hub, there being a plurality of sets 11' of bristles from one side of the hub to the other. The periphery 12 of the bristles as a whole is rounded as shown in Figures 1 and 4 so as to fit into the fillet c between the gum portion b and body portion a on the dental plate.

The brush is held in place on the stem 5 by a washer 13 held in contact with the shoulder 8 by a thumb nut 14 screwed over the threaded 10 extremity 9. Sufficient clearance is provided between the shoulder 7 and shoulder 8 of the stem 5 so that the brush is freely rotatable on said stem 5.

A plate sector 15 is secured to face f of hub 15 10 and is provided with an arcuate slot 16 for receiving a pin 17 traversing an opening 17' in the shank 2. Said pin is connected to a bellcrank 18 pivotally mounted on a lug 19 projecting from the shank 2 of handle 1, and a wire link 19' extends downwardly from the bellcrank lever alongside the handle 1 to which it is held by an eye 20. The free end of the link 19' is provided with a loop 21 for the finger of the operator whereby on pushing upwardly on the link 19' the lever 18 is rocked to cause pin 17 to enter slot 16, and on pulling downwardly on the link 19' the lever 18 is rocked to withdraw the pin 17 from the slot 16.

As stated above, the brush may be rotated 30 along the fillet c of the plate, and because of its shape will follow the contour of this fillet so that every part thereof may be contacted by the brush and the accumulations thereon loosened and removed.

35 The advantage of the pin 17 and plate 15 is that if desired the brush may be arrested after partial rotation so as to operate as an ordinary brush in removing accumulations from the dental plate P. In other words, we have the 40 combined action of a brush rolling over the parts to be cleaned and then brushing the loosened accumulations therefrom.

While I show an upper dental plate in Fig. 1, 45 it should be obvious that a lower dental plate may be treated in the same manner by my improved brush.

From the foregoing description it is apparent 50 that my improved brush may be applied to the dental plate, together with tooth powder or tooth paste, and moved back and forth over the surface thereof to thoroughly cleanse the same without any danger of injuring the plate as only the bristles can come in contact therewith.

The brush when worn may be readily replaced on the holder, making for economy in use.

Having described my invention, I claim:

- 5 1. A dental plate cleanser comprising a handle and a brush comprising a hub and a mass of bristles extending entirely around said hub and projecting radially therefrom, and a coupling device interposed between the handle and the brush for a predetermined limited lost rotary motion.
- 10 2. A dental plate cleanser comprising a han-

dle, a shank projecting from one end of said handle, a brush comprising a hub and a mass of bristles extending entirely around said hub and projecting radially therefrom, the bristles being rounded transversely to the periphery of the 5 brush, said brush being rotatably mounted on said shank, and a coupling device interposed between the handle and the brush for a predetermined limited lost rotary motion.

10

SAMUEL JELLINEK.
